UNITED STATES PATENT OFFICE.

JAMES F. EVERETT, OF CHICAGO, ILLINOIS, ASSIGNOR, BY DIRECT AND MESNE ASSIGNMENTS, OF ONE-FIFTH TO BERNARD F. SCHMIDT, ONE-FIFTH TO GEORGE W. FORD, ONE-FIFTH TO CHARLES F. BURROWS, AND ONE-FIFTH TO WILLIAM T. DELIHANT, ALL OF CHICAGO, ILLINOIS.

WASHING MACHINE.

Application filed July 15, 1922. Serial No. 575,336.

To all whom it may concern:

Be it known that I, JAMES F. EVERETT, a citizen of the United States, and a resident of the city of Chicago, county of Cook, and State of Illinois, have invented certain new and useful Improvements in Washing Machines, of which the following is a specification.

My invention relates to improvements in washing machines and more particularly to washing chambers therefor, the object of the invention being to provide a simple and efficient washing chamber which is capable of economical manufacture and is highly efficient in use.

Other objects will appear hereafter.

The invention consists in the combinations and arrangements of parts hereinafter described and claimed.

The invention will be best understood by reference to the accompanying drawings forming a part of this specification, and in which,

Fig. 1, is a vertical transverse section of a washing machine equipped with a washing chamber embodying the invention,

Fig. 2, is a section at right angles to Fig. 1,

Fig. 3, is an enlarged detailed section through a portion of the periphery of the washing chamber.

The preferred form of construction, as illustrated in the drawings, comprises an outer substantially hemispherical bowl 4, preferably made of concrete material and mounted on a suitable pedestal or base 5, as indicated. A removable cover 7, also substantially hemispherical in form, is secured to the bowl 4, as shown, and provided with a suitable door 8. The bowl 4 is provided with a suitable distributing passage or channel 9 into which leads a supply pipe 10 by means of which the washing fluid is supplied to the interior of the washing machine. A suitable discharge valve 11 is provided in the bottom of the bowl 4 for discharging the washing fluid.

Arranged within the casing thus formed is a revolving washing chamber, or drum, 12 substantially globular in form and consists of two hemispherical halves, each provided with a trunnion 13 suitably mounted to rotate in the outer casing of the machine,

as indicated. Each of the hemispherical halves is provided around its edges with an inwardly extending flange 14 having recesses 15 in the sides thereof, said flanges being positioned adjacent each other and spot-welded, or otherwise secured to each other, to complete the globular chamber. Each part of the chamber is also provided with ribs 16 arranged perpendicularly, as shown, to the central spreader rib formed by the juncture of the flanges 14, there being four of the ribs 16, as indicated. The flanges 14 are made of less height than the ribs 16 at the intersections and increase in height toward the points 17 midway between said ribs 16, thus forming recesses 18 which tend to lift the clothes within the washing chamber as the same revolves. Hubs 19 are also formed in the interiors of the washing chamber parts at the junctures of the ribs 16 and whereby the formation of acute angle recesses at these points is prevented. The washing chamber parts are each formed from a single casting and subsequently secured together to complete the washing chamber the walls of which are perforated to admit the washing water thereto.

One of the trunnions 13 carries the driving gear 20 meshing with a pinion 21 on an electric motor 22 and by means of which the washing chamber will be constantly driven in one direction. A suitable door 12' is provided for the washing chamber and by means of which the clothes to be washed may be readily inserted or removed.

In use the clothes are placed in the washing chamber and a suitable amount of washing fluid supplied to the machine. The washing chamber is then constantly rotated in one direction, the clothes being picked up by the ribs 16 and carried upwardly thereby until they reach a position adjacent the top when they fall through gravity. The recesses 15 in the sides of the spreader rib 14—14 tend to form vacuums to cause the clothes to cling to said rib, thus assisting in this lifting action. Likewise, the recesses 18 tend to form effective engagement of the clothes with the lifting rib 16 and thus facilitate this lifting action. In this way the clothes will be quickly and efficiently washed without entanglement.

The form and arrangement of the washing chamber disclosed is a simple and efficient one which may be manufactured economically.

5 While I have illustrated and described the preferred form of construction for carrying my invention into effect, this is capable of variation and modification without departing from the spirit of the invention.

10 I, therefore, do not wish to be limited to the precise details of construction set forth, but desire to avail myself of such variations and modifications as come within the scope of the appended claims.

15 Having described my invention, what I claim as new and desire to secure by Letters Patent is:

1. A washing machine comprising a washing chamber substantially spherical in form and mounted to rotate upon a horizontal axis; and a spreader rib substantially at the center of the inner walls of said chamber and extending around the axis of rotation in a plane substantially perpendicular thereto, 25 the sides of said rib being provided with recesses, substantially as described.

2. A washing machine comprising a washing chamber substantially spherical in form and mounted to rotate upon a horizontal axis; and a spreader rib substantially at the center of the inner walls of said chamber and extending around the axis of rotation in a plane substantially perpendicular thereto, said spreader rib being of different 35 heights at different portions thereof, substantially as described.

3. A washing machine comprising a washing chamber substantially spherical in form and mounted to rotate upon a horizontal axis; a spreader rib substantially at the center of the inner walls of said chamber and extending around the axis of rotation in a plane substantially perpendicular thereto, said spreader rib being of different heights 40 at different portions thereof; and the sides of said spreader rib being provided with recesses, substantially as described.

4. A washing chamber for washing machines substantially spherical in form and mounted to rotate upon a horizontal axis; ribs on the inner walls of said washing chamber extending along the inner periph- 50

ery thereof from points adjacent the axis of rotation on one side to corresponding points adjacent the axis of rotation on the other side; and a spreader rib substantially at the center of said chamber and extending around the axis of rotation in a plane substantially perpendicular thereto, said spreader rib being higher midway between said first mentioned ribs and decreasing in height toward said first mentioned ribs, substantially as described.

5. A washing chamber for washing machines substantially spherical in form and mounted to rotate upon a horizontal axis; ribs on the inner walls of said washing chamber extending along the inner periphery thereof from points adjacent the axis of rotation on one side to corresponding points adjacent the axis of rotation on the other side; a spreader rib substantially at the center of said chamber and extending around the axis of rotation in a plane substantially perpendicular thereto, said spreader rib being higher midway between said first mentioned ribs and decreasing in height toward said first mentioned ribs, and the sides of said spreader rib being provided with recesses.

6. A washing chamber for washing machines comprising two substantially hemispherical parts; and inwardly extending flanges at the edges of said parts adapted and arranged to be secured together to form a substantially globular chamber, substantially as described.

7. A washing chamber for washing machines comprising two substantially hemispherical parts; inwardly extending flanges at the edges of said parts adapted and arranged to be secured together to form a substantially globular chamber; and ribs on the inner walls of said parts substantially perpendicular to the flanges thereof, substantially as described.

In testimony whereof I have signed my name to this specification in the presence of two subscribing witnesses.

JAMES F. EVERETT.
